ASH TRAY

Jean-Louis Poivrel and Marie Charles Hubert
Michelang, Paris, France

Application June 22, 1938, Serial No. 215,158

10 Claims. (Cl. 220—29)

Ash-trays or ash containers of various types are known, where the emitting of smoke from the cigar or cigarette butts is prevented. The main disadvantages of the known types consist in the fact that the containers are emptied but with difficulty or that their manipulation is onerous and that always nicotine and ash remnants remain visible on the receiving surface.

According to the present invention a receptacle is created for ashes, cigar and cigarette ends or the like, the novel feature of which consists in an aperture adapted to be closed either by a collecting plate for ash or the like or by a closure plate, the collecting plate and closure plate being so arranged that when the collecting plate is in use the aperture is closed by the closing plate. When the collecting plate is put out of operation the aperture of the receptacle opens automatically in such a manner that the smoking remnants drop from the collecting plate into the receptacle while the collecting plate closes the aperture. Thus, by this arrangement is attained the result that the remnants contained in the receptacle are entirely sealed towards the outside during the use of the ash-tray. In addition to this advantage an exceedingly easy manipulation, a pleasing appearance and a completely clean surface when out of use is achieved.

The accompanying drawings show some embodiments of the invention.

Fig. 1 is a perspective representation of an ash receptacle constructed in accordance with the invention.

Fig. 2 is a sectional view of the ash receptacle taken on line 2—2 of Fig. 4.

Fig. 3 is a sectional view of another embodiment of an ash receptacle taken on line 3—3 of Fig. 5.

Fig. 4 is a side elevational view of the ash receptacle shown in Fig. 2, the collecting plate, however, being shown in ash receiving position, and

Fig. 5 is a side elevational view of the ash receptacle shown in Fig. 3.

As shown in Figs. 1, 2 and 4 the ash receptacle consists substantially of a receiving body 1 of any desired shape which, for instance, is laterally provided with one or more apertures for throwing in the ashes, cigars or cigarette butts. This aperture may be closed in two ways according to whether the device is in or out of use. In Figs. 1 and 4 the device is illustrated in a position ready for use. In this position a cigarette 4 may be placed upon the collecting plate 2 pivoted to the

receptacle at 3 near the lower edge of the aperture. The collecting plate serves as an ash collector during the smoking. The aperture of the container 1 is closed by a plate 5 which is suspended on a bar 7 by means of rings, loops or the like. The ends of the bar 7 are held, for instance, in the side walls of the container 1. The collecting plate 2 is connected with the closure plate 5 by means of arms 8. The arms 8 are suspended at both ends for instance, in ring parts attached to the closure plate 5 and the collecting plate 2 respectively, in such a manner that a linkage connection is provided between the closure plate 5 and the collecting plate 2.

After having used the collecting plate 2, i. e. when smoking has been stopped or when considerable amounts of refuse have been collected in this collecting plate the latter is pivoted by pressure from below upwards, whereby the closure plate 5 is pivoted around its upper edge towards the interior of the receptacle, this movement giving access to the opening of the container's aperture, the ashes dropping from the collecting plate 2 into the interior of the container.

When the collecting plate 2 is entirely pivoted upwards it is caught or held by a catching device or locking means 9. The catching device 9 consists, for instance, of a pin bent upwards at its lower end and subjected to the force of a spring 19. The bent end may be caught by a projection 11 on the edge of the collecting plate 2. When the latter is held in this closing position, the closure plate 5 and the connecting bars 8 occupy approximately the position shown in Fig. 2.

The bottom part of the ash receptacle may be formed by a plate 10 which can be pulled out. If this plate 10 is pulled off, the total contents of the ash receptacle may be removed. The removal may, of course, be effected also by the collecting plate 2 being pivoted from the position shown in Fig. 1 but only to a certain extent, e. g., 45° upwards, thus enabling the contents of the ash receptacle to be thrown out easily through the aperture which is only partly closed by the closure plate 5.

Figs. 3 and 5 show another embodiment of the invention. As may be seen from the illustration a closing plate 15 is provided for the aperture of the container. This plate is pivotally arranged on a bar 12 held in the side walls of the container and is rigidly connected with an arm 14. If a pressure is applied from above to the arm 14 by a push button 13 the plate

pushes against a cam or projection 16 of the collecting plate 2, whereupon the latter drops around its hinge 18 into a position ready for use as shown in Fig. 3 on the left hand side. The collecting plate 2 is provided with an extension 17 which presses against the lower edge of the plate 15 thus holding this plate in the position as shown on the left hand side of Fig. 3. Hereby the aperture of the container is kept closed while the collecting plate 2 is in use. When after use the collecting plate 2 is swung up from below, the extension 17 swings downwards and the plate 15 is able to drop back into the position as drawn on the right hand side.

Having now particularly described and ascertained the nature of our said invention and in what manner the same is to be performed, we declare that what we claim is:

1. A receptacle for ashes or the like with at least one aperture in its walls for the delivery of ashes into the receptacle, comprising a collecting plate for ashes or the like arranged on the outside of said wall and movably mounted on the receptacle near the lower edge of said aperture, said collecting plate being adapted to be brought into a first position for receiving ashes and into a second position for delivering ashes through said aperture and closing same, a closure plate arranged on the inside of said wall and movably mounted on the receptacle near the upper edge of said aperture, said closure plate being adapted to be brought into a first position for closing said aperture and into a second position for opening said aperture, and means whereby movement of said closure plate to closing position is adapted to cause movement of said collecting plate to ash receiving position and whereby movement of said collecting plate to ash delivery position is adapted to cause movement of said closure plate to opening position.

2. A receptacle for ashes or the like with at least one aperture in its walls for the delivery of ashes into the receptacle, comprising a collecting plate for ashes or the like arranged on the outside of said wall and movably mounted on the receptacle near the lower edge of said aperture, said collecting plate being adapted to be brought into a first position for receiving ashes and into a second position for delivering ashes through said aperture and closing same, a closure plate arranged on the inside of said wall and movably mounted on the receptacle near the upper edge of said aperture, said closure plate being adapted to be brought into a first position for closing said aperture and into a second position for opening said aperture, and a cooperative connection between said collecting plate and said closure plate whereby said closure plate is in closing position when said collecting plate is in ash receiving position.

3. A receptacle for ashes or the like with at least one aperture in its walls for the delivery of ashes into the receptacle, comprising a collecting plate for ashes or the like arranged on the outside of said wall and pivoted to the receptacle near the lower edge of said aperture, said collecting plate being adapted to be swung into a first position for receiving ashes and into a second position for delivering ashes through said aperture and closing same, a closure plate arranged on the inside of said wall and pivoted to the receptacle near the upper edge of said aperture, said closure plate being adapted to be swung into a first position for closing said aperture and into a second position for opening said

aperture, holding means arranged on said collecting plate, said holding means extending into the receptacle when the collecting plate is in its first position, and cam means arranged on said collecting plate, said cam means extending into the receptacle when the collecting plate is in its second position, said closure plate being adapted to contact with said cam means of said collecting plate for swinging same into ash receiving position when the closure plate is swung into closing position, said holding means being adapted to engage with said closure plate for holding same in closing position when said collecting plate is in ash receiving position, and said holding means becoming disengaged from said closure plate to permit movement of said closure plate to opening position when the collecting plate is swung into ash delivery position.

4. A receptacle as claimed in claim 3, an arm being arranged on said closure plate, and a push button being movably arranged in said receptacle, said push button being in engagement with said arm for causing a swinging movement of said closure plate into closing position.

5. A receptacle as claimed in claim 3, in which the pivot point of the closure plate is arranged at a place of the receptacle permitting an automatic swinging movement of the closure plate by gravity from the closing position into the opening position when the holding means is disengaged from said closure plate.

6. A receptacle for ashes or the like with at least one upwardly inclined wall and an aperture therein for the delivery of ashes into the receptacle, comprising a collecting plate for ashes or the like arranged on the outside of said inclined wall and pivoted to the receptacle near the lower edge of said aperture, said collecting plate being adapted to be swung into a first position for receiving ashes and into a second position for delivering ashes through said aperture and closing same, a closure plate arranged on the inside of said inclined wall and pivoted to the receptacle near the upper edge of said aperture, said closure plate being adapted to be swung into a first position for closing said aperture and into a second position for opening said aperture, means for swinging said closure plate into closing position, holding means arranged on said collecting plate, said holding means extending into the receptacle when the collecting plate is in its first position, and cam means arranged on said collecting plate, said cam means extending into the receptacle when the collecting plate is in its second position, said closure plate being adapted to contact with said cam means of said collecting plate for swinging same into ash receiving position when the closure plate is swung into closing position, said holding means being adapted to engage with said closure plate for holding same in closing position when said collecting plate is in ash receiving position, and said holding means becoming disengaged from said closure plate so that said closure plate swings by gravity into opening position when the collecting plate is swung into ash delivery position.

7. A receptacle for ashes or the like with at least one aperture in its walls for the delivery of ashes into the receptacle, comprising a collecting plate for ashes or the like arranged on the outside of said wall and pivoted to the receptacle near the lower edge of said aperture, said collecting plate being adapted to be swung into a first position for receiving ashes and into a second position for delivering ashes through

said aperture and closing same, a closure plate arranged on the inside of said wall and pivoted to the receptacle near the upper edge of said aperture, said closure plate being adapted to be swung into a first position for closing said aperture and into a second position for opening said aperture, and cam means arranged on said collecting plate, said cam means extending into the receptacle when the collecting plate is in its second position, said closure plate being adapted to contact with said cam means of said collecting plate for swinging same into ash receiving position when the closure plate is swung into closing position.

8. A receptacle for ashes or the like with at least one aperture in its walls for the delivery of ashes into the receptacle, comprising a collecting plate for ashes or the like arranged on the outside of said wall and pivoted to the receptacle near the lower edge of said aperture, said collecting plate being adapted to be swung into a first position for receiving ashes and into a second position for delivering ashes through said aperture and closing same, a closure plate arranged on the inside of said wall and pivoted to the receptacle near the upper edge of said aperture, said collecting plate being adapted to be swung into a first position for closing said aperture and into a second position for opening said aperture, and holding means arranged on said collecting plate, said holding means extending into the receptacle when the collecting plate is

in its first position and being adapted to engage with said closure plate for holding same in closing position when said collecting plate is in ash receiving position.

5 9. A receptacle for ashes or the like with at least one aperture in its walls for the delivery of ashes into the receptacle, comprising a collecting plate for ashes or the like arranged on the outside of said wall and pivoted to the receptacle near the lower edge of said aperture, said collecting plate being adapted to be swung into a first position for receiving ashes and into a second position for delivering ashes through said aperture and closing same, a closure plate arranged on the inside of said wall and pivoted to the receptacle near the upper edge of said aperture, said closing plate being adapted to be swung into a first position for closing said aperture and into a second position for opening said aperture, and a linkage connection between said collecting plate and said closure plate whereby movement of said closure plate to closing position is adapted to cause movement of said collecting plate to ash receiving position and whereby movement of said collecting plate to ash delivery position is adapted to cause movement of said closure plate to opening position.

10 15 20 25 30 10. A receptacle as claimed in claim 9 including locking means for holding the collecting plate in ash delivery position.
